FIRE ALARM SIGNAL BOX

Robert Stafford Edwards, New Canaan, and Leo L. Verkuil, Norwalk, Conn., assignors to Edwards Company, Inc., Norwalk, Conn., a corporation of New York

Application October 30, 1950, Serial No. 12,780

Term of patent 14 years

(Cl. D72—1)

To all whom it may concern:

Be it known that we, Robert Stafford Edwards and Leo L. Verkuil, citizens of the United States of America and residents, respectively, of New Canaan and Norwalk, both in the county of Fairfield and State of Connecticut, have invented a new, original, and ornamental Design for a Fire Alarm Signal Box, of which the following is a specification, reference being had to the accompanying drawing, forming a part thereof, in which—

Figure 1 is a front elevational view of a fire alarm signal box showing our new design;

Figure 2 is a side elevation as seen from the right in Figure 1;

Figure 3 is a top plan view thereof; and

Figure 4 is a perspective view of the fire alarm signal box.

We claim:

The ornamental design for a fire alarm signal box, as shown.

ROBERT STAFFORD EDWARDS.
LEO L. VERKUIL.
